UNITED STATES PATENT OFFICE.

ROBERT ERNST FISCHER AND MAX WESCHER, OF ELBERFELD, GERMANY.

STACKING MECHANISM FOR PRINTING, FOLDING, OR SIMILAR PAPER-TREATING MACHINES.

958,798.

Specification of Letters Patent. Patented May 24, 1910.

Application filed April 2, 1909. Serial No. 487,421.

To all whom it may concern:

Be it known that we, ROBERT ERNST FISCHER and MAX WESCHER, subjects of the German Emperor, residing at Elberfeld, in 5 the Kingdom of Prussia, German Empire, have jointly invented new and useful Improvements in Stacking Mechanism for Printing, Folding, or Similar Paper-Treating Machines, of which the following is the 10 specification.

Our invention relates to improvements in stacking mechanism for printing, folding or similar paper treating machines and it has for its object to enable the work to be 15 stacked so that the pieces of paper or the like are piled so as to have their edges lying in a vertical plane. We attain this object by the mechanism illustrated in the accompanying drawing in which:

20 Figure 1 is a side view and Fig. 2 a front view of the mechanism. Fig. 3 illustrates a modified construction of part of the same.

25 *a* is a roller over which the papers, envelops or the like pass into the receiver. *b* is a fixed wall or member composed of stationary rails forming part of the receiver against which the papers strike and along which they slide downward. *d* is another fixed wall or member composed of stationary 30 guide rails closing the receiver at its rear side.

f and *g* are vibrating leaf springs, which press the papers during their fall as well as after the same are situated upon the pile, 35 against the rails *d* and *b*. The spring *f* is secured to the shaft *h* carrying the lever *i* and participates in its movements. This lever *i* carries a roller *k* running on the cam plate *l* and thus causes the spring *f* to vibrate. The shaft *h* also carries a pin or 40 projection *m* which presses on a pin *o* connected with a second shaft *n* in such a manner that this shaft is likewise caused to vibrate. The second spring *g* is connected 45 with the shaft *n* in such a manner that the spring *f* always oscillates outward when the spring *g* oscillates inward. Now when the sheets of paper, envelops, or the like reach the receiver constituted by the rails *b* and *d* 50 and the springs *f* and *g*, they are pressed by the spring *f* against the rails *b* and by the spring *g* against the rails *d*, so that they

slide downward along these rails and so that they lie one above the other on the pile in a perfectly vertical manner. It is of 55 great importance for the correct operation of the springs, that they should be operative alternately, the result of this being that harmful friction is avoided as one spring is unable to impede the action of the other in 60 causing the sheets of paper displaced by one spring to pass over the other spring.

Instead of the leaf springs *f* and *g* the vibrating members may consist of curved rails as shown in Fig. 3 the curved portion 65 of these rails being provided with steps or corrugations *p*. The vertical portions of these steps bear against the sheets during their fall.

It will be understood, that the construction 70 described is only an example and that the construction may be modified in different ways, so for instance several vibrating members may be provided on one side or the vibrating members may be provided on all 75 the four sides of the receiver, the idea of the invention consisting in regulating the position of the paper during their fall as well as on the pile.

We claim:

1. In a stacking device the combination of 80 stationary members forming two sides of the receiver, curved rails provided with steps forming the other side of the same and means for alternately operating the curved 85 rails of one or the other side whereby the sheets of paper will be supported by and pushed into place by said steps, substantially as described and for the purpose set forth.

2. In a stacking machine, the combination 90 with the receiver consisting of stationary and rocking members, a rock shaft upon which one of said rocking members is mounted, means for rocking said shaft, a second rock shaft upon which the other rocking 95 member is mounted and connections between said shafts whereby said members will be advanced alternately in planes at an angle to each other.

3. In a stacking machine, the combination 100 with the receiver consisting of stationary and rocking members, a rock shaft upon which said rocking member is mounted, a pin or projection carried by said shaft,

means for rocking said shaft, a second rock shaft arranged at substantially right angles to said first shaft, a projection on said second shaft, with which the pin on the first shaft 5 coöperates, the pin and projection being so positioned relatively to each other that as one shaft is rocked inward the other is rocked outward and vice versa.

In testimony whereof we have signed our names to this specification in the presence of 10 two subscribing witnesses.

ROBERT ERNST FISCHER. [L. S.]
MAX WESCHER. [L. S.]
